US0D1010590S

(12) **United States Design Patent** (10) **Patent No.:** **US D1,010,590 S**
(45) **Date of Patent:** **** Jan. 9, 2024**

(54) **CONTROL DEVICE**

(71) Applicants: **GD MIDEA AIR-CONDITIONING EQUIPMENT CO., LTD.**, Foshan (CN); **MIDEA GROUP CO., LTD.**, Foshan (CN)

(72) Inventors: **Yongtao Li**, Foshan (CN); **Guanqiu Qiu**, Foshan (CN); **Jiho Jung**, Foshan (CN)

(73) Assignees: **GD MIDEA AIR-CONDITIONING EQUIPMENT CO., LTD.**, Foshan (CN); **MIDEA GROUP CO., LTD.**, Foshan (CN)

(**) Term: **15 Years**

(21) Appl. No.: **29/837,574**

(22) Filed: **May 6, 2022**

(30) **Foreign Application Priority Data**

Jan. 19, 2022 (CN) 202230036639.0

(57) **CLAIM**

The ornamental design for a control device, as shown and described.

DESCRIPTION

FIG. 1 is a front right perspective view of a control device in accordance with the present disclosure;

FIG. 2 is a front left perspective view of the control device shown in FIG. 1;

FIG. 3 is a view of the control device shown in FIG. 1 from the front;

FIG. 4 is a view of the control device shown in FIG. 1 from the rear;

FIG. 5 is a view of the control device shown in FIG. 1 from the left;

FIG. 6 is a view of the control device shown in FIG. 1 from the right;

FIG. 7 is a view of the control device shown in FIG. 1 from the top; and,

FIG. 8 is a view of the control device shown in FIG. 1 from the bottom.

The broken lines in the figures show portions of the control device that form no part of the claimed design.

1 Claim, 8 Drawing Sheets
